UNITED STATES PATENT OFFICE

2,530,970

DOUBLE-ACTING INTERNAL-COMBUSTION
ENGINE

Robert H. Jones, Jr., Lubbock, Tex.

Application May 23, 1949, Serial No. 94,832

5 Claims. (Cl. 123—63)

1

This invention relates to gas or Diesel engines of the reciprocating type, having one or more cylinders, and its principal object resides in the provision of a novel cylinder and piston arrangement in which each cylinder has a firing head on each end and the piston therein is adapted to be operated in both directions in the cylinder to actuate a crank through the medium of a rigid piston rod slidably journaled in one end of the cylinder, and providing means for operating fuel intake and exhaust valves by a crank wheel connected to the crank.

Another object of the invention is that of providing an economically operated motor, capable of use in driving automobiles, boats, aircraft, or the like, or as a stationary power unit, and afford a light and compact assembly which may be connected directly to the driven element, such as an air compressor, or the like, and provide a motor having a minimum of operating parts to reduce friction.

Broadly, the invention contemplates the provision of an internal combustion engine which is adapted to be constructed so that a four cycle engine can be provided while employing only two cylinders and a single piston in each, both pistons operating on a single rigid piston or connecting rod to rotate a crank wheel and drive shaft.

While the foregoing objects are paramount, other and lesser objects will become manifest as the description proceeds, taken in connection with the appended drawings wherein:

Figure 1 is a longitudinal cross-sectional view on lines 1—1 of Figure 2 through the cylinder of the preferred form of the invention showing the double acting piston, rigid connecting rod, crank and crank wheel.

Figure 2 illustrates the cylinder in elevation and shows the fuel lines, spark plugs, valve actuating push rods and rocker arms.

Figure 3 is a fragmentary view showing the details of the push-rod and rocker arm assembly for the lubricating valves.

Figure 4 is a longitudinal cross-sectional view of a modification of the invention, showing a combustion cylinder and piston therein, and illustrating a compressor cylinder and piston, the pistons being connected by a single rod.

Figure 5 is a transverse cross-sectional illustration through the cylinder and piston, on lines 5—5 of Figure 4, showing the lubricating injector device, and

Figure 6 is a face view of the crank wheel of the structure shown in Figure 4, the crank case being fragmentarily shown in section.

2

Accordingly, the preferred construction, shown in Figures 1 and 2, comprises a cylinder 10 which may be either air or water cooled, as desired. The invention is illustrated as equipped with suitable fins 11 and 12 formed, respectively, circumferentially of the cylinder 10 or transversely of the axes of the cylinder heads 13 and 14.

It will become apparent that the inner cylinder head 14 is partially enclosed in the crank case 15 which also houses the crank and crank wheel 17, both of which will be presently described more fully. The head 14 is formed internally with a boss 18 and a sleeve 19, the latter being shown formed with the inner wall of the crank case 15. Thus is provided a bore 20 through which a piston rod 21 is slidably arranged. The piston or connecting rod 21 is rigidly attached at one end to the piston 22 operating in the cylinder 10 while its opposite end has a crank pin 23 formed thereon and extending at right angles from the rod. A plurality of suitable packing rings 24 are arranged in grooves formed on the rod 21 to provide a seal within the bore 2.

A crank 25 is operatively attached to the pin 23 through a non-friction bearing 26. The crank 25 is shaped with the portion 27 containing the bearing 26 in alignment with the rod 21 and another portion 28 is in a plane parallel to the pin 23. Thus, the arm 29 of the crank 25 is offset with respect to the portion 27 although in a plane parallel thereto. A non-friction bearing 30 is provided for the pin 31 of the crank wheel 17 which comprises a pair of spaced disks separated by the pin 31 and the bearing 30 in the end of the crank 25.

A stub shaft is provided on each side of the wheel 17 rotatably supporting the same. The inner shaft 32 is journaled in a bearing 33 supported in a recess formed in the cylinder 10 within the crank case 15 while the outer shaft 34 has a bearing 35 in the outer wall of the crank case 15 and functions also as a drive or pulley shaft. The crank 25 is strengthened by an integral web 36 arranged along the side of the right-angular portion 28 and joining the bearing portion 27.

A set of intake and exhaust ports with their valves are arranged in each of the cylinder heads 13 and 14. The intake port 37 and outlet port 38, in the head 13, are closed by poppet valves 39 and 40, respectively, which are operated by push-rods 41 to actuate the rocker arms 42 and 43. A set of push-rods 41' actuate the intake and exhaust valves 43 and 44, respectively, which close the intake ports 45 and exhaust ports 46 in the opposite head 14, an arrangement of rocker arms

41 and 48 being operatively connected to the valve stems. Fuel lines 49 and 50 are connected to the cylinder heads 13 and 14 through the intake ports 37 and 45, and spark plugs 51 are arranged in the heads as is apparent in Figure 2.

The piston 22 is lightened by forming the same with a single wall 52 intermediate its ends. The rod 21 may be threaded into the member 52 which has a boss 53 formed therewith. A circumferential groove 54 is defined about the outer wall of the piston 22 through which the cylinder walls are lubricated from a duct 55 communicating with the crank case 15. Oil from the crank case 15 is injected into the cylinder 10 by a piston 56 in a chamber 57 which has a port opening into the cylinder 10 normally closed by a check valve 58.

The piston 56 is actuated by a lug 59 on the crank wheel 17 which engages the stem 60 of the piston 56 on each revolution, or if more frequent operation is desired, a plurality of lugs 59 may be provided. The piston 56 is arranged on one side of the cylinder 10 intermediate its ends and the mechanism is timed to inject lubricants into the cylinder 10 at the moment the circumferential groove 54 of the piston 22 is aligned therewith.

The oil is discharged from the cylinder 10 on the opposite side thereof through a port 61, which has a valve 62 therein, and is conducted through a suitable conduit back to the crank case 15. The valve 62 is actuated in proper timing by a rocker arm 63 operatively attached to the outside of the cylinder 10 and moved by a cam 64 formed on one of the push-rods 41.

The push rods 41 and 41' are operated by cams 65 on a cam shaft 66 driven through a gear train 67 from the shaft 32 of the crank wheel 17. The cams 65 are substantially oval in shape and their operative faces are engaged by the feet 68 on the ends of the push-rods 41 and 41', as shown in Figures 2 and 3. The rods 41 and 41' are arranged in guides 69 integral with the cylinder 10.

It is to be observed that the crank case 15 is shaped so that a relatively flat or thin portion 70 is extended at right angles from one side and this portion houses the rods 21 and its pin 23 with the bearing 26.

An example of the several uses of the invention is illustrated in Figures 4, 5 and 6. Obviously, the motor can be constructed with a pair of cylinders arranged opposite each other, each having identically designed pistons connected by a rigid connecting rod having a driving connection with a crank wheel so that each piston can be operated from either end of its respective cylinder, the firing order being so timed as to insure proper function.

In Figure 4 is illustrated, in longitudinal section, a motor embodying the features of the invention and having an air compressor attached directly to the piston of the engine. The invention is modified in this adaptation, as will presently become apparent. In this structure a cylinder 71 is provided which is designed very similarly to the cylinder 10 of the structure shown in Figures 1, 2 and 3, and has a piston 72 operating therein which is also similar to the piston 22, having a circumferential lubricating groove 73. Both ends or heads 74 and 75 of the cylinder 71 are equipped with intake and exhaust ports 76 and 77 with their valves 78 and 79. The ports 76 and 77 in one head are arranged transversely to those in the opposite head. The head 75 has

an inner boss 80 and an outer sleeve 81 formed therewith to provide a bore 82 and guide for the rigid connecting rod 83 which is secured to the piston 72 in the same manner as the piston 22 is attached to the rod 21. Packing rings 84 are arranged on the rod 83 in the bore 82 to seal the cylinder 71.

The crank case 85 is attached to one end of the cylinder 71 and encloses the head 75 and houses the connecting rod 83 and the crank wheel 86 with its connection to the rod 83. Opposite the cylinder 71, and on the opposite end of the crank case 85, is a compressor cylinder 87 having a piston 88 therein connected to the rod 83 opposite the piston 72. The piston 88 is formed similar to the pistons 22 and 72 but functions only as a compressor piston. Both cylinders 71 and 87 have cooling fins 89 formed thereon.

The crank wheel 86 is driven by a roller assembly, comprising a pair of rollers 90 and 91 pivoted to a rotatable disk 92 operatively secured to the face 93 of the wheel 86. The roller assembly is eccentrically arranged on the wheel 86 and the rollers 90 and 91 thereof are spaced apart to engage both sides of a bar 94 rigidly secured to the rod 83 intermediate its ends and transversely thereof. Thus, as the rod 83 is reciprocated the wheel 86 is rotated, the rollers 90 and 91 moving to and fro on the bar 94, as illustrated in dotted lines in Figure 6. The disk 92 has a stub shaft 95 which is arranged in a bearing 96 in the wheel 86, the latter having its stub shaft 97 journalled in bearings 98 housed in a bearing box 99 formed with the crank case 85.

The intake and exhaust valves in the head 74 of the cylinder 71 are operated, or opened and closed, by push rods 100 one end of which have feet 101 engaging cams 102 arranged on a cam shaft 103 journalled at each end in the crank case 85 and driven by a sprocket chain 104 by the wheel 86 through a sprocket arranged on the shaft 97 and a sprocket 97' on the cam shaft 103. The outer ends of the push rods 100 engage and operate rocker arms 105 which are operatively connected to the stems 106 of the valves. The valves in the opposite head 75 are opened by cams 107 on the shaft 103. Obviously, the cams 102 and 107 should be timed to actuate the valves in proper synchrony with the firing of the cylinder 71. The cylinder 71 is lubricated from the crank case 85 through suitable conduits connected to a port 108 in a side of the cylinder 71, the lubricant being injected by a piston 109 housed in a chamber 110, as shown in Figure 5, and controlled by a check valve 111. A return port 112 for the lubricant is also provided and has a check valve 113 therein.

The piston 109 is actuated, in proper synchrony, by a push rod 114 which is moved by a cam 115 on one of the push rods 100, a rocker arm (not shown) being the medium by which motion is transmitted from the rod 114 to the stem 116 of the injector piston 109, as illustrated in Figure 5. The communications from the chamber 110 and the discharge port 112 are separated by an integral rib 117 formed on the piston 72 and transversely of the groove 73. In this manner the lubricant will enter the groove 73 and flow around to the discharge port 112, thence back to the crank case.

The compressor cylinder 87 is lubricated from the crank case through a system of valves 118 in the side of the cylinder similarly to the arrangement described in the cylinder 71. The

injector piston is operated by a rocker arm and push rod 119 which has an operative connection with a cam 120 on the shaft 97 of the crank wheel. The cam 120 is arranged in the box 99 between the bearings 98. The compressor piston 88 may also function to compress air in both ends of the cylinder 87 and the intake and exhaust ports 121 and 122 in one end must be in transverse arrangement in the opposite end, and suitable check valves 123 and 124 are provided.

It is manifest that certain changes and modifications in the structure may be resorted to from time to time, by persons skilled in the art without departing from the spirit and intent of the invention or the scope of the appended claims.

What is claimed is:

1. In a reciprocating type of gasoline engine, in combination, a cylinder having intake and exhaust valves in each end, a piston in said cylinder adapted to be actuated from either end, a rod connected to said piston and slidably supported in a bearing forming part of one head of said cylinder, the said rod having a right-angular pin on its end opposite said piston, a crank connected to said pin and having a portion offset at right angles between its ends, the opposite end of said crank having an operative connection to a crank wheel, a crank case enclosing said crank and said wheel, valve means providing for lubricating said cylinder from said crank case, and means actuated by said wheel operating said intake and exhaust valves and said lubricating valves.

2. In a gas engine of the reciprocating type, in combination with a cylinder and a piston operating therein, an arrangement of intake and exhaust valves in each end of said cylinder whereby said piston is driven in both directions in said cylinder, a piston rod connected to said piston capable of operation longitudinally of said cylinder and journaled through one end of said cylinder, a crank pin formed on said piston rod and a crank connected to said pin, a crank wheel operatively associated with said piston and having a driven connection with the opposite end of said piston rod, a crank case enclosing said crank wheel, means operated by said wheel providing for lubricating said cylinder from said crank case, and means operated by said wheel actuating said intake and exhaust valves.

3. In a gas engine having a double acting

piston and a crank wheel, in combination with a cylinder having an intake and exhaust valve in each end, a piston rod connected to said piston and slidably journaled through one end of said piston and having a driven connection with said crank wheel, a crank case enclosing said crank wheel and piston rod, valve controlled means for lubricating said cylinder from said crank case, and cam means actuated by said crank wheel for operating said valve controlled lubricating means and said intake and exhaust valves.

10 4. In a gas engine having a cylinder and a piston operating therein capable of being driven

15 in each direction, in combination, a rod connected to said piston and slidably through one end of said cylinder, a crank case enclosing said rod and a crank wheel having an operative connection with said rod in said crank case, fuel intake and exhaust valves arranged in each end of said cylinder and operating in synchrony with said piston, automatic means for lubricating said cylinder, and means actuated by said crank wheel operating said intake and exhaust valves and said automatic lubricating means.

20 5. In a gas engine of the character described having a cylinder and a double-acting piston therein, in combination, intake and exhaust valves arranged in the ends of said cylinder, a piston rod connected to said piston and slidably operating through one end of said cylinder, a crank case enclosing said rod, a crank wheel having a driven connection with said rod and arranged in said crank case, means for injecting a lubricant into said cylinder from said crank case, and means actuated by said crank wheel for operating said lubricant injecting means and said inlet and exhaust valves.

ROBERT H. JONES, JR.
